DOWEL BAR ADJUSTING AND ALIGNING DEVICE

John N. Heltzel, Warren, Ohio; The Union Savings & Trust Company of Warren, Ohio, and Carl J. Heltzel, executors of said John N. Heltzel, deceased

Application September 18, 1946, Serial No. 697,699

4 Claims. (Cl. 94—51)

1

The present invention relates to improvements in dowel bar adjusting and aligning devices and more particularly refers to adjusting and aligning devices for use in connection with the dowel bars and dowel sockets and/or dowel bar bearing elements for load transfer devices currently employed in connection with concrete constructions, such as airport runways, concrete roads and the like in which individual slabs of concrete are individually poured and laid with dowel bars tying adjacent slabs together in an unitary construction which nevertheless admits of local expansion and contraction of the individual slabs.

In actual practice, unless the dowel bars, sockets or bearings are installed with their axes in exact parallelism it is difficult to withdraw the bulkheads or side forms because the openings in such bulkheads will jam against bent, misaligned or distorted dowel bars in the process of the bulkheads being slid longitudinally of the dowel bars in disassembling the bulkhead from the dowel bars after the initial slab has been poured and hardened.

At the same time, such dowel bars must be in exact alignment with the plane of the finished surface of the roadway; otherwise contracting and expanding movement of one slab relatively to the other will require that one slab ride upwardly thus causing surface disalignment at the joint and rapid deterioration of the concrete edge due to traffic movement over the same.

The failure of dowel bars in the respects above noted has been caused by misalignment of the bars during the pouring of the concrete, which renders the dowel bars ineffective and detrimental to the roadway to such an extent that many highway engineers are opposed to the use of dowel bars regardless of the apparent necessity of their use in order to maintain the slabs in surface alignment.

With the foregoing and other objects in view, the invention will be more fully described hereinafter and more particularly pointed out in the appended claims.

In the drawings, in which like parts are denoted by the same reference characters throughout the several views,

Figure 1 is a perspective view of a conventional side form showing an improved dowel bar adjustment and alignment device in place as constructed in accordance with the present invention.

Figure 2 is a vertical cross-section taken on the lines 2—2 in Figure 3.

Figure 3 is a fragmentary longitudinal section taken on the lines 3—3 in Figure 2.

2

Figure 4 is a horizontal section taken on the lines 4—4 of Figure 2.

Referring more particularly to the drawings the invention is shown as used in connection with a type of bulkhead which is embodied in a standard road form composed of the usual vertical web 11, base 12, top rail 13 and upstanding base flange 14.

Such bulkheads or side forms have usually been provided with a series of openings 15 through the web 11 to receive the dowel bars 16 which are to extend into adjacent slabs of the completed concrete construction.

In accordance with the present invention I propose to depart from standard practice by appreciably and substantially enlarging the diameters of the openings 15 over the external diameters of the dowel bars 16 to allow for ample play and clearance of the central portions of the dowel bars which occupy such openings 15 to the end that such dowel bars may be adjusted therein in a universal manner, that is in all angular directions of tilting movement about the central portions of the dowel bars and also to permit the dowel bars a limited movement of translation up and down and to the sides horizontally in a universal manner to the end that such dowel bars may be brought to a correctly aligned position where the axes of all of the dowel bars of a single bulkhead or side form may be in true and exact parallelism and whereby the axes of the dowel bars may all be precisely parallel to the plane in which the surfaces of the slabs lie. Furthermore the enlarged openings 15 will permit of easier disassembly and removal of the bulkhead from the dowel bars after one slab has been poured and finished as indicated in Figure 1; the enlarged openings 15 affording greater clearance whereby the walls of the openings 15 will not readily jam against any of the free ends of the dowel bars 16 which project from the finished slab and over which the bulkhead or side form must be slid in the act of removal of such bulkhead or side form from the slab; inasmuch as such free ends of the dowel bars 16 may become disaligned.

The invention further contemplates a device for positively aligning the dowel bars and for that purpose utilizes the bulkhead or side form as a rigid abutment with reference to which both a horizontal and vertical aligning and adjusting action may take place.

A support 22 in the form of a metallic thin plate is arranged with its lower portion slidable externally longitudinally of the base flange of the bulkhead with a base toe 10 extending beneath

the base 12 of the side form. The lower end portion of the support 22 acts as one member of a clamp, the other clamp member being formed by the lower inwardly offset section 26 of a plate having an upper section 25 which is in substantial vertical alignment with the flange 14 and which fits against the inner face of the support 22. An offset shoulder 27 connects the two sections 25 and 26.

The support 22 and plate section 26 may be frictionally tightly gripped together upon the bulkhead flanges 12 or 14 by the use of a clamp operating device of any suitable form. In the drawings a clamp bolt or shaft 30 passes rotatably through the support 22 and upper plate section 25 and may be rotated by means of a handle or crank 28. A boss 32 on the bolt 30 engages the outer face of the support 22 while a nut 31 threaded on the inner end of the bolt 30 is tightened by the rotary action of the bolt in one direction against the upper plate section 25. In other words, when the crank 28 is rotated in one direction the nut 31 will be advanced outwardly toward the boss 32 in order to bind the plates together in clamping relation; while reverse rotation of the bolt 30 will cause the nut 31 to move outwardly from the boss 32 thus relaxing the clamp and thus permitting the support 22 to be slid to a new position longitudinally along the bulkhead flange 14 or removed when desired. The nut 31 will have to be held stationary by hand or by a wrench or other tool.

Carried adjustably upon the upper portion of the support 22 is an adjusting plate 18 having an opening 39 therein of the approximate diameter of the external diameter of the dowel bar 16 in order to rather snugly receive the free end portion of such dowel bar to compel this end portion of the dowel bar to follow the movements of the plate 18.

Such plate 18 may also be formed with an upper outwardly projecting lip or flange 40 to offer engagement to the fingers to facilitate the lifting of the plate 18 relatively to the support 22 on which such adjusting plate 18 is carried.

Back of the adjusting plate 18, the support is formed with a slot 33 through which the dowel 16 also projects. The slot 33 is elongated in a vertical direction or in a direction of adjustment of the plate 18 on the support 22 thus permitting the end of the dowel bar 16 to move up and down in its slot 33 in obedience to the adjustment imposed upon it by the adjusting plate 18. This slot 33 will also be of sufficient width to accommodate the dowel bar 16 and also certain other accessories which may or may not be used in connection with the adjusting device.

Also the slot 33 may be extended up sufficiently far to receive therethrough the bolt or shaft 41 of a clamping device adapted to retain the clamping plate 18 in adjusted position. This bolt 41 is threaded upon its inner end portion to receive thereon a travelling nut 38 which may take directly against a backing plate 37 adapted to bridge the upper portion of the slot 33 at the inner side of the support 22. A boss 35 on the bolt 41 is of sufficient diameter to bridge the width of the vertically elongated slot 36 which may be provided in the adjustment plate 18 for the passage of the bolt 41. The bolt 41 may be rotated conveniently by the use of a handle or crank 34. If desired a round opening may be used in place of the slot 36, such round opening being only sufficient in diameter to encompass the clamp bolt 41. In other words it may not in

all cases be necessary to provide both slots 36 and 33 in the vicinity of the clamp bolt 41. One such slot will be sufficient for permitting of the raising and lowering adjusting movement of the clamp plate 18.

As a further feature of the invention which may or may not be used in connection with the adjusting device, a reducer plug 21 is adapted to fit removably in each enlarged opening 15 and to have an opening therethrough for freely slidably receiving the dowel bars 16. A lip 20 outstanding from the inner portion of the plug is of sufficient diameter to engage the inside face of the web 11 of the bulkhead in order to limit the axial movement of the plug 21 and to prevent the plug 21 from being pushed through the opening 15. The external diameter of the plug 21 will preferably be somewhat less than the internal diameter of the opening 15 into which it fits in order to permit the plug to have a limited rocking movement in the opening 15 as a fulcrum for the dowel bar 16 in the act of raising and lowering or moving the dowel bar side to side in the act of adjusting the same, and the lip 20 will cutstand in such relative position as to permit of its limited rocking movement; or the plug might fit snugly in the opening 15 and sufficient clearance provided between the internal opening of the plug and the dowel bar 16 to allow of this adjusting movement of the dowel bar.

A preferably rigid connection 19 may be made between the plug 21 and the adjusting plate 18; this rigid connection being in the form of an angle iron, a tube or the like; such connection 19 communicating thrust from the plate 18 to the plug 21 for the purpose of pushing the plug into the opening 15 from an operator's position at the adjusting device.

It will be seen particularly from Figure 3 that the slot 33 will have sufficient horizontal width not only to clear the side edges of the connection 19 but also to admit the lip 20 although the width of slot 33 may be slightly less than the external diameter of the lip 20 inasmuch as such lip may be rocked through the slot 33 in the act of assembling the device to the bulkhead or road form.

In the use of the device the support 22 and its clamp are assembled to the flange 14 or base 12 of the side form as shown and inasmuch as the adjusting plate 18 is carried by the support 22 any longitudinal motion of the support 22 along the flange 14 will communicate a movement in a horizontal direction to the dowel bar 16 thus causing the dowel bar to be brought to a correct axial position in parallelism with the axes of all other dowel bars of the side form or in other words to bring its axis into a position at right angles to the vertical plane of the web 11 when so desired. After this horizontal adjustment has been effected the lower clamp is tightened to hold the support 22 directly in place while the upper clamp is relaxed to permit the adjusting plate 18 to be easily raised or lowered carrying the dowel bar 16 therewith so as to accurately adjust the dowel bar in a vertical sense to a position with its axis exactly parallel with a plane passing through the surfaces of the slabs. After adjustment both clamps are tightened to maintain the dowel bar 16 rigidly in the adjusted position during the pouring, vibrating and surfacing of the concrete at the opposite side of the bulkhead or side form.

Where the reducer plug is used, the same is carried through the connection 19 by the plate

18 so that such connection 19 and reducer plug 21 participate in the movements of the plate 18 although the plug 21 acts as a shifting fulcrum about which such adjusting movement may be achieved as well as the adjusting movement of the plate 22 in horizontal directions. However, the reducer plug takes up the additional clearance space of the opening 15 during the assembling and pouring operations and provides support for the dowel bar 16 during such assembling and pouring operations.

It will be understood that a number of adjusting devices will be provided in proportion to the number of dowel bars associated with any particular bulkhead or side form and that such adjusting devices may all be independent structurally and operatively of one another or the same may be connected together for simultaneous adjustment, as indicated by longitudinal aligning member, being adjustably supported at its ends by securing to adjusting plate 18 thereby intermediate dowels are simultaneously adjusted. Will be more fully described in later application.

After the slab 42 has set as it is desired to remove the bulkhead or side form therefrom, the adjusting device is first removed by relaxing the clamp 28 to a point where the inner member of the clamp 26 may be rotated upwardly about the clamp bolt 30 as a center to a position where the plate section 26 will clear the bulkhead flange 14 whereupon the entire device, including the rigid connection 19 and the reducer plug 21, may be withdrawn axially over the dowel bar 16 which then leaves free all of the dowel bars and the enlarged openings 15 whereby the bulkhead or side form may then readily be slid over the dowel bars and removed from the same and from the concrete. The bulkheads and side forms and the adjusting devices may then be removed to a new site for further paving operations.

The reducer plug 21 may be urged into position by the tubular member 19 so that when clamped in position the instrumentalities cooperating for the purpose intended will force the reducer plug against the form and prevent its being disengaged therefrom during the placing and finishing of the concrete. However such reducer plug is very readily removed after its purpose has been served.

It will be understood that the adjusting device receives and supports the dowel bar during the placing and surfacing of the concrete.

One means for adjusting simultaneously all the dowel bars of a given bulkhead or side form is shown in Figure 1 in which two adjusting devices of the character previously described are mounted on the side form and associated with the end dowel bars. The intermediate dowel bars have each a perforated intermediate plate 45 associated therewith in which the perforated plate fits rather snugly over the exposed end of the dowel bar. A longitudinal supporting bar 46 is affixed to all of the perforated intermediate plates 45 and the two vertically adjustable plates 18 of the two end adjusting devices. In this way all of the dowel bars are tied together for simultaneous horizontal and vertical adjustment. If desired, plugs similar to plug 21 may be mounted in the intermediate openings 15.

In addition, in Figure 1 I have illustrated a socket 16A with a bearing member 16B constituting a load transfer unit, which members may be separate or integral and staked or otherwise erected on the subgrade. The reason for this arrangement is that it is apparent on some types

of structure it might be the desire of the engineer to spot the socket, accommodating the dowel bars to be inserted later. In that case dowel bars are removed from the socket after the bearing members on load transfer elements have been spotted.

While I have disclosed herein but one form of the invention, other forms are known to me at the present time and are being manufactured. Other applications are in process. I desire it to be understood that I reserve the right to make changes and modifications in the herein described embodiment of the invention provided such changes fall within the scope of the appended claims.

What I claim is:

1. In combination, a road form having a web and a base flange, said web having openings therethrough, dowel bars extending through said openings, the diameters of said openings being materially in excess of the external diameters of said dowel bars, supports carried by said base flange and adjustable longitudinally of said road form, clamps for clamping said supports to said road form in adjusted position, reducer plugs fitted over the dowel bars and into the enlarged openings in said web, vertical adjusting means carried by said longitudinally adjustable supports and having openings therethrough to snugly receive said dowel bars, and connections between said vertical adjusting means and said reducer plugs for maintaining the reducer plugs in the road form opening.

2. In combination with a road form having an opening therethrough to receive a dowel bar, said opening being materially in excess of the diameter of a dowel bar, a dowel bar adjusting and aligning device comprising a reducer plug of less diameter than said opening and received within said opening between the dowel bar and said road form, a support, detachable connecting means connecting said support to said road form for selective attachment along said road form, said support having an opening therethrough to receive a dowel bar, and a plate having means adapted to support the outer portion of a dowel bar and adjustably mounted for vertical adjustment on said support, whereby said plate requires the dowel bar to be adjusted with it vertically relatively to said support and horizontally when the plate and support are together adjusted along the road form.

3. A dowel bar adjusting and aligning device comprising a reducer plug adapted to fit within an opening within the web of a road form and to receive a dowel bar, a vertically adjustable member, means connecting the reducer plug to said member in spaced relationship, a support, detachable clamping means on said support for selective attachment along said road form and means for adjustably mounting the member on said support, whereby the reducer plug is movable vertically and horizontally of the road form.

4. In combination, a road form having a web and a base flange, said web having an opening therethrough for receiving a dowel bar, the diameter of said opening being materially in excess of the external diameter of a dowel bar, supporting means carried by said base flange, detachable means connecting said supporting means to said base flange for selective attachment along said base flange, a reducer plug adapted to fit over a dowel bar and fitting into the enlarged opening in said web, a member adjustable vertically on said supporting means and having an opening there-

through to snugly receive a dowel bar, and a connection between said member and said reducer plug for maintaining said reducer plug in the road form opening.

JOHN N. HELTZEL.
